SOCK FORM

Samuel J. Johnsen, Cincinnati, Ohio, assignor to
 The Seinsheimer Paper Company, Cincinnati,
 Ohio, a corporation of Ohio

Application February 4, 1932. Serial No. 590,925

1 Claim. (Cl. 223—17)

This invention relates to garment supporting or mounting means and is particularly directed to a form for supporting or mounting socks.

It is the object of this invention to provide a form of this nature which supports the sock in such wise as to retain the true or original shape of the sock particularly in the operation of drying socks and of special importance in the supporting of woolen socks.

Another object of this invention is to provide a form device of this character to which the sock is readily applied and which is sectional and thereby capable of variation as to foot size for accommodating the different sizes of socks, and moreover to provide a perforated form over which the sock may be disposed for drying purposes.

Other objects and certain advantages will be more fully apparent from a description of the accompanying drawing, in which:

Figure 1 is a perspective view showing the form in detail.

Figure 2 is a sectional view taken on line 2—2, Figure 1, illustrating the adjustable structure of the form.

Figure 3 is a side view of the form showing a sock mounted thereon and illustrating the form suspended from a support rod.

The form 5 as regarded generally is constructed of sections 6, 7, preferably of cardboard. The joint between the two pieces or sections of the form is along the foot portion of the sock. Therefore, upon reference to the drawing it will be found that one of the members or sections, namely 6, provides the supporting form for the upper part of the sock including the heel and ankle portion thereof. The second section or member 7 is adjustably fixed to the foot portion of the first section and forms the extended foot and toe portion thereof.

The adjustment movement between these parts takes place along the foot portion so that the length of the foot portion may be varied. To this end, adjustment slots 8, 9 are provided in the respective members parallel with and along the foot portions thereof. Attaching screws 10 are disposed through the adjacent slots and are screwed into nut elements 11. The nut elements include flanges 12 bearing against the outer side of the particular element and countercurned portions 13 fitted slidably within the slot. By positioning these fastening elements through the slots and sliding the elements thereon, the length of the form may be varied to suit the particular size of sock being stretched. Upon the proper

length being determined and provided, the fastening devices may be set by tightening the screws.

The body of the form is perforated as at 14, the size and number of the perforations being variable. The device is adapted to be hung on a rod or support 16 by means of a hook 15 pivotally fixed to the upper end of the form by means of an attaching pin 17 riveted in place in the material.

The material may be impregnated with some type of water resisting liquid for rendering the material impervious to moisture whereby the paper structure will not be damaged by the contact therewith of a wet sock mounted thereon for the purpose of drying the sock in its proper shape. This device is readily adaptable for use in supporting socks during storage but is especially beneficial in its use as a form for socks during the process of drying. The apertures through the form permit the passage of air therethrough and thereby increase the speed of the drying operation.

The forms are of extreme benefit in the operation of drying woolen socks inasmuch as the socks have no opportunity to shrink or assume irregular or distorted shapes. The true form of the sock is retained and the socks may be left on the form until needed.

Having described my invention, I claim:

A sock mounting device, comprising, a form constructed of waterproof sheet material having the contour of a flattened sock, said form of sectional construction along the foot portion thereof for extending the foot, said sections having adjacently disposed slots therein extending longitudinally of the foot portion, and a plurality of fastening devices extended through said slots and adapted to be spaced along the slots, whereby the sections may be fixed in any desired extended position and are maintained in alignment.

SAMUEL J. JOHNSON.
